UNITED STATES PATENT OFFICE.

WILLIAM F. SMITH, AND EDWIN P. SANFORD, OF FLINT, MICHIGAN.

INDICATOR.

1,333,190.

Specification of Letters Patent.

Patented Mar. 9, 1920.

Application filed May 16, 1916, Serial No. 97,874. Renewed August 6, 1919. Serial No. 315,786.

To all whom it may concern:

Be it known that we, WILLIAM F. SMITH and EDWIN P. SANFORD, citizens of the United States, residing at Flint, in the 5 county of Genesee and State of Michigan, have invented certain new and useful Improvements in Indicators; and we do hereby declare the following to be a full, clear, and exact description of the invention, such as 10 will enable others skilled in the art to which it appertains to make and use the same.

Our invention relates to new and useful improvements in indicators and more particularly to that class adapted to be used for 15 indicating street crossings, railway stations, and the like, and our object is to provide a cabinet in which are positioned rollers which are adapted to receive and wind thereon a belt having the names of various streets or 20 stations printed thereon, which names are adapted to be successively brought into registration with a visual space or window in one face of the cabinet.

A further object is to provide electrically 25 operated means for rotating said rollers to wind the belt thereon.

Means for reversing the travel of the belt,

Means to regulate the movement of parts 30 of the device employed for rotating the rollers,

And means for energizing parts of the operating mechanism by a current taken from a trolley wire.

With these objects in view, the invention 35 consists in the improved construction, arrangement, and combination of parts hereinafter fully described, and afterward specifically claimed.

In the accompanying drawings,

40 Figure 1 represents a rear elevation of the cabinet showing the means for rotating the rollers,

Fig. 2, a side elevation thereof,

45 Fig. 3, a side elevation of the upper part of a trolley pole and wire showing means for obtaining current from the trolley wire to operate the indicator,

Fig. 4, a top plan view thereof, and

50 Fig. 5, a top plan view of the lower end of the trolley pole and parts to which it is connected.

Referring to the drawings in which similar reference numerals designate corresponding parts throughout the several figures, 1

indicates the cabinet which may be constructed in any preferred manner and of any preferred material, preferably of wood, in one wall of which is provided a visual space or slot 2 before which travels a belt 3, attached to rollers 4 and 5, mounted upon 60 shafts 6 and 7 which project through one side wall of the cabinet and have driven gears 8 and 9, respectively, attached thereto.

The belt 3 passes from the rollers 4 and 5 around the guide rollers 10 positioned adjacent the forward face of the cabinet so that it will be brought in close proximity to the visual space 2 as it travels from one roller to the other. The upper roller 4 is rotated in one direction by means of a gear 11 carried by a shaft 12 and an idle gear 13 interposed between the gears 8 and 11, the shaft 12 having a ratchet 14 fixed thereon with which cooperates a spring pressed pawl 15 carried by a lever 16, rotatable on the shaft 12, and as the lever is successively rocked upon the shaft 12, the gear 11 and other gears meshing therewith will be rotated. The shaft 12 carrying the gear 11 is rotatably mounted in a substantially U-shaped frame 17, having slots 18 through which the shaft 7 extends, while the side wall of the cabinet is likewise provided with a slot 19 through which the shaft 12 projects. An adjusting screw 20 is extended through an opening in the lower end of the U-shaped frame 17 and threaded into the cabinet. Collars are fixed on the screw 20 to rotatably bear on opposite sides of the frame 20, whereby when the screw is adjusted the frame may be moved up or down to throw the gear 11 into and out of engagement with the gears 13 and 9. When the gear 11 is lowered into engagement with the gear 9 and the lever 16 is rocked, the roller 5 will be rotated and the belt wound thereon.

The lever 16 is rocked upon the shaft 12 by attaching thereto one end of a plunger 21, the opposite end of the plunger cooperating with a coil 22 of a solenoid 23, said solenoid being attached at any convenient point to the side of the cabinet 1, and when a flux is set up in the coil the plunger 21 is attracted and moved upwardly through the solenoid, thereby rotating the gear 11 a predetermined distance, the breaking of the circuit through the solenoid releasing the pull from the plunger, whereupon the weight of the same will

swing the lever to its lowered position ready to again impart rotating motion to the gear when the plunger is again elevated. When the indicator is used in connection with 5 street railways or interurban cars, the electricity for operating the solenoid is obtained from the trolley wire 24 by attaching to the stay wire 25, usually employed for supporting the trolley wire, a contact finger 26 depending from the stay wire and in position 10 to be engaged by a contact arm 27 carried by the trolley pole 28.

The current is conducted from the contact arm 27 through a wire 29 to a circular plate 30, attached to the lower end of the trolley pole and rotatable therewith, the current being conducted from the plate 30 through a brush 31 positioned below the plate and through a wire 32 to one pole of the solenoid. The opposite pole of the solenoid is connected to a wire 33 thence through 20 a resistance coil 34 to the ground, said wire 33 having a switch 35 for controlling the circuit through the solenoid.

25 In operation, when the car is traveling in one direction and the switch 35 in the wire 33 is closed, the contact of the arm 27 with one of the fingers 26 will electrically energize the coil 22 and move the plunger 21 vertically a sufficient distance to bring the name of the next street or station to position 30 in front of the visual space 2, this operation being successively performed by properly positioning the contact fingers 26 along 35 the trolley line, and when the end of the route has been reached the adjusting screw 20 is operated and the gear 11 moved downwardly out of mesh with the idle gear 13 and into mesh with the gear 9 so that when the 40 car starts on its return journey the belt containing the names of the streets will be re-wound upon the roller 5, the solenoid being intermittently energized by placing contact fingers on the opposite side of the 45 trolley wire where a single track is used, or upon one side of an additional trolley wire where double tracks are used.

In order to control the stroke of the plunger 21 so that the belt may be moved 50 a universal distance with each operation of the solenoid, collars 36 and 37 are adjustably secured upon the plunger 21 on opposite sides of a stop 38, said stop being fixed to the side of the cabinet 7 in position 55 to be engaged by said collars, and by adjusting the collars at different points on the plunger, the stroke of the plunger may be readily regulated.

In connection with the indicator, additional gears and rollers may be placed in the cabinet to receive and operate a belt containing advertising matter which is to be operated in the same manner and at the same time as the operation of the belt containing 65 the names of the streets or stations.

It will further be seen that this device can be very cheaply manufactured and readily installed for use, and in view of the simplicity of the parts they will be practically indestructible from use.

It will likewise be seen that the operation of the device can be entirely stopped by operating the switch and that the movable gear may be quickly transferred from one gear to the other to rotate the belt in opposite directions and by providing the circular plate at the lower end of the trolley pole, which is adapted to rotate with the trolley pole, a connection between the wires 29 and 30 is always provided when the arm 80 27 engages one of the fingers 26.

Having thus fully described our invention what we claim as new and desire to secure by Letters Patent of the United States, is:—

1. In an indicator, the combination with 85 a cabinet having a vertical slot in one side thereof, a top and a bottom roller journaled in the sides of the cabinet, a belt secured to both rollers and adapted to be alternately wound on each of said rollers, a driven gear on the end of the shaft of each roller outside of the cabinet, a stub shaft secured in the side of the cabinet, an idler gear on the stub shaft meshing with the driven gear of the upper roller, 95 a vertical U-shaped frame embracing one side wall of the cabinet and having a vertical slot through which the shaft of the lower roller passes, a stub shaft journaled in the U-shaped frame and entering the vertical slot in the cabinet, a driving gear on the last named shaft, means to adjust the height of the U-shaped frame to cause the driving gear to engage either the driven gear of the lower roller or the idler gear, 100 and means to rotate the driving gear in either adjustment.

2. In an indicator, the combination with 110 a cabinet having a vertical slot in one side thereof, a top and a bottom roller journaled in the sides of the cabinet, a belt secured to both rollers and adapted to be alternately wound on each of said rollers, a driven gear on the end of the shaft of each roller outside of the cabinet, a stub shaft secured in the side of the cabinet, an idler gear on the stub shaft meshing with the gear of the upper roller, a vertical U-shaped frame embracing one side wall of the cabinet and having a vertical slot 115 through which the shaft of the lower roller passes, a stub shaft journaled in the U-shaped frame and entering the vertical slot in the cabinet, a driving gear on the last named shaft, means to adjust the height 120 of the U-shaped frame to cause the driving gear to engage either the gear of the lower roller or the idler gear, a ratchet wheel on the driving gear, a lever loosely journaled on the driving gear shaft, a pawl on the 125 130

lever to engage the ratchet wheel, a solenoid secured to the side of the cabinet, a plunger in the solenoid attached at its lower end to the outer end of the lever and recipro-
5 cable by the energizing and deenergizing of the solenoid, and means for limiting the extent of movement of the plunger.

In testimony whereof we have signed our

names to this specification in the presence of two subscribing witnesses.
